UNITED STATES PATENT OFFICE

112,520

DESIGN FOR A TOWEL DISPENSING CABINET

Burton E. Ebert, Lansdowne, Pa., assignor to Scott Paper Company, Chester, Pa., a corporation of Pennsylvania

Application October 5, 1938, Serial No. 80,278

Term of patent 14 years

To all whom it may concern:

Be it known that I, Burton E. Ebert, a citizen of the United States, residing at Lansdowne, Pennsylvania, have invented a new, original, and ornamental Design for a Towel Dispensing Cabinet, of which the following is a specification, reference being had to the accompanying drawing, forming part thereof, in which:

Figure 1 is a view in perspective of a towel dispensing cabinet showing my new design, and
Fig. 2 is an inverted plan view.

I claim:

The ornamental design for a towel dispensing cabinet, substantially as shown.

BURTON E. EBERT.
